FILLING MACHINE

Ralph B. Bagby, Evanston, Ill.

Original application September 30, 1932, Serial No. 635,621. Divided and this application February 6, 1936, Serial No. 62,581

4 Claims. (Cl. 221—102)

My invention relates to machines for filling containers with viscous materials such as ice cream, cheese, salad dressing, etc., and particularly to details of a multi-cylinder machine having novel features of improvement. This application is a division of my copending application, Pat. No. 2,032,163, filed September 30, 1932.

An object of my invention is to provide a filling machine adapted to simultaneously deliver two kinds or colors of materials to a single container and to segregate such materials until actually delivered to the container.

A further object is to provide a multiple cylinder machine of the character described having the capacity for ready removal of all of the parts that contact the material being handled to enable cleaning thereof.

The invention will be more readily understood by reference to the accompanying drawing, in which;

Fig. 1 is a plan view of a machine constructed in accordance with my invention;

Fig. 2 is an end view thereof;

Fig. 3 is a sectional view on the line 3—3 of Fig. 2, and;

Fig. 4 is an enlarged perspective view of the filling nozzle.

In the accompanying drawing I have shown a base 10 on which the parts of the machine about to be described are mounted. For receiving a quantity of the material to be handled, a hopper 11 is provided and extending diametrically thereacross is a partition 12 dividing the hopper into independent sections. At the discharge end of the hopper is a casting 13, which is bolted onto overhanging arms at one end of the member 14. Secured to the underside of the casting 13 is a valve housing 15 having an oscillatory valve member 16 mounted in a bore therein. The valve member 16 has two recesses such as 17 therein. The valve member 16 has trunnions at opposite ends thereof, one of which extends through a cover plate 18 and has an arm 19 connected thereto. An opening 20, Fig. 3, is provided in the valve housing through which communication is established between the opening 20 and the recesses 17. On the side of the valve housing opposite the inlet 21 is an outlet 22. Secured to the underside of the valve housing 15 is a filling tube T and this tube communicates with the outlet 22. A partition 23 divides the opening 20 into two parts and this partition is aligned with the partition 12 in the hopper 11. A partition 24 in the inlet 21 includes a rounded edge embracing the valve member 16 and this

partition is aligned with the partition 23. A partition 25 divides the outlet 22 into two parts and a partition 26 divides the filling tube T into two parts. An inturned lip 27 is provided at the lower end of the filling tube T and the corners of the partition 26 are cut away as indicated at 28 so that the partition may rest on the lip 27. It is manifest that the separated chambers in the various parts are isolated from each other and consequently when different materials are introduced into the hopper 11, these materials may be independently withdrawn from the separate compartments and independently discharged through the filling tube T. The foregoing arrangement enables me to fill containers with different substances at the same time and if the viscosity of the substances is sufficient to prevent free flowing thereof, the materials are segregated in the container.

In order to independently withdraw the materials from the separate compartments in the hopper 11, I provide independent cylinders 29 and 30 which are screw-threaded into the side of the valve housing in substantially right-angular relationship with the inlet 21 and the outlet 22, independent openings such as 31 being provided in alignment with the cylinders 29 and 30. The base 10 includes an upstanding portion and projecting from the upper end thereof parallel to the base are two rods 32 and 33. Sleeves 34 and 35 are respectively slidable along the rods 32 and 33 and are interconnected by a rod 36 rotatable in bearings provided in the sleeves 34 and 35. Piston rods 37 and 38 extend between the rod 36 and pistons such as 39 respectively reciprocal in the cylinders 29 and 30. One end of a pitman 40 is rotatively connected to the rod 36, intermediate the piston rods 37 and 38, and the end of the pitman opposite that connected to the rod 36 is enlarged and has an opening 41 therein. A screw 42 extends into the opening 41 from the free end of the pitman and has a lock nut 43 thereon to retain it in position. A stud 44 extends through the opening 41 and is connected to the disk 45 fast on the shaft 46. The shaft 46 is journaled in bearings provided in a gear case 47 in which gear case a suitable speed reducing mechanism is provided which is connected to a shaft of the motor 48. When the motor 48 is set in operation, the shaft 46 is rotated which causes rotation of the disk 45 whereupon movement is transmitted through the pitman 40 to the rod 36 and thence through the piston rods 37 and 38 to the pistons in the cylinders 29 and 30. To rotate the valve member 16, 55

a track cam 49 is provided which is integral with the disk 45, Fig. 1. Through the medium of suitable mechanism 50 and the connecting rod 51, movement is transmitted to the arm 19 for rotating the valve in timed relation.

The parts are so timed that when the pistons are at the inner ends of the cylinders 29 and 30 and during the lost motion subsequent to movement of the stud 44 through dead center position adjacent the cylinders, the track cam causes the valve member to be oscillated so as to position the recesses 17 in the full line position shown in Fig. 3 and at the end of the lost motion the stud 44 engages the inner end of the screw 42 and consequently the pistons are caused to move rearwardly through the cylinders to withdraw material from the individual compartments in the hopper and this material passes into the cylinders. During the lost movement subsequent to movement of the stud 44 through dead center position remote from the cylinders, the track-cam 49 causes the valve member 16 to so move that the recesses 17 are arranged in the broken line position of Fig. 3 and at the end of the lost motion, the pistons move forwardly through the cylinders and expel the material from the cylinders whereupon the material passes through the filling tube into a container positioned therebelow. It is essential that the partition 26 be provided in the filling tube for otherwise the materials would intermingle while passing therethrough and segregation thereof would be impossible. It is to be understood that the dividing partitions may be omitted and that the machine may be used to fill but one substance, and it may so be used when the partitions are employed. Furthermore, the divisions and number of cylinders and pistons may be increased without departing from the purview of the invention.

It is manifest from the foregoing description that I have provided a filling machine wherein a predetermined quantity of material may be withdrawn from a supply thereof and introduced into a chamber. The machine includes a filling tube which insures complete filling of the containers and which prevents waste of the material. Moreover, the valve controlling communication between the cylinders and the supply and discharge devices remain entirely open during the movement of the pistons through the cylinders and consequently there is no restricted passage during the last portion of the movement of the pistons in opposite directions. Furthermore, the device is so arranged that the pistons are always returned to forward position but by arranging adjustable means in different positions, the amount of rearward movement of the pistons and consequently the amount of material withdrawn from the storage devices may be expeditiously varied.

It will be seen that by removal of the end plate 18, the rotary valve may readily be displaced endwise and cleaned. In order to clean the cylinders and pistons, the cylinders are un-

screwed from the valve body, as best shown in Fig. 3, and when so disconnected, are slid rearwardly until free from the valve casting and the hopper and are then swung into the dotted line position of Fig. 3 whereupon the cylinders may be slid endwise from engagement with the pistons and both the cylinders and pistons may be thoroughly cleaned. This provides a quick and easy method of removing and replacing the cylinders, an operation that should be performed at frequent intervals.

I claim:

1. In a filling machine, a valve body having valve means therein for controlling discharge from said machine, said valve body having at least two spaced outlet openings therein with a web therebetween, and means including a tube providing a discharge passage leading from said outlet opening, and a plate mounted in said tube to extend thereacross and longitudinally therethrough and aligned with said web, whereby distinguished substances flowing through said outlet openings are kept segregated during flow thereof through said tube.

2. In a filling machine, a valve body having valve means therein and provided with at least two spaced outlet openings, a pair of cylinders in separable engagement with said valve body, pistons in said cylinders, and rods for the pistons, a cross head engaging said rods, means for effecting reciprocation of said cross head, the rods being mounted for oscillation on the cross head thereby permitting said pistons and associated cylinders when they are disengaged from the valve body, to be oscillated into a position in which the cylinders may be separated from the pistons.

3. In combination, a valve body, a valve therein having two passages, said valve body having a threaded opening in communication with each of said passages, cylinders having screw threaded ends adapted to be engaged in said openings, a cross head including a rotatable shaft, rods connecting said pistons to said shaft, a pitman also connected to said shaft, the arrangement being such that the cylinders may be disengaged from the valve body then oscillated with said pistons and rods into a position in which the cylinders may be disengaged from the pistons.

4. In combination, a valve body and a valve therein, said valve body and valve having a plurality of registering passages, a plurality of cylinders readily removably connected to said valve body and registering with said passages, pistons in said cylinders, a cross head including a rotatable member, means for reciprocating said cross head, piston rods connecting the pistons to said rotatable member, the arrangement being such that said cylinders may be disengaged from the valve body and swung with the pistons to a position where the cylinders and pistons may readily be separated.

RALPH B. BAGBY.
